UNITED STATES PATENT OFFICE

2,107,563

DISPENSING CAP

Edward L. Chott, Chicago, Ill., assignor of one-half to Hugo J. Chott, Chicago, Ill.

Application May 6, 1936, Serial No. 78,077

6 Claims. (Cl. 221—106)

This invention relates to devices for measuring tooth filling material and has for its main object to provide a new and improved device of this character.

5 Another object of the invention is to provide a simple, practical and efficient device of the character described.

Another object is to provide a device for dispensing uniform quantities of tooth filling material such as powdered metal.

The invention consists in a novel construction of the device and in the parts and combinations as hereinafter described and pointed out, particularly in the appended claims.

15 Referring more particularly to the accompanying drawing forming a part of this specification and illustrating a practical adaptation of the invention:

Fig. 1 is a side view of the device;

20 Fig. 2 is a similar view at right angles to the position of Fig. 1;

Fig. 3 is a top view of the device of Fig. 1;

Fig. 4 is an inverted cross-section taken along the line 4—4 of Fig. 3, enlarged and showing a 25 portion only of the container;

Fig. 5 is a cross-section taken along the line 5—5 of Fig. 4;

Fig. 6 is a detail view of the measuring cylinder partly in central section; and

30 Fig. 7 is a detail view of one of the friction cap pins.

Referring more particularly to the drawing, I show a dispenser having a container portion 10 provided with a threaded neck 11 and a dispensing cap 12 preferably of cylindrical shape, having an internally threaded portion 13 for cooperation with threaded neck 11 of container 10. The cap 12 has a cross bore 14, the ends of which are provided with circular grooves 15. A receiving port 16 extends from the inner portion of the cap to the cross bore 14 and a similar port 17 is provided. A discharge port 18 is arranged in alignment with receiving port 16 and extends from cross bore 14. A similar discharge port 19 is provided, aligned with receiving port 17. A slot 20 extends across discharge ports 18 and 19 and is adapted to provide a friction bearing for a rotary measuring cylinder 21. Cylinder 21 has a cylindrical or ring shoulder 22 adapted to rotate in one of the circular grooves 15 and is further provided with a knurled operating stem 23 at one end. The opposite end of the cylinder 21 has a bore 24 having threads 24a in which fits a lock screw 25 which retains a washer 26 which seats in the adjacent groove 15. A cylindrical

5 pocket 27 is provided in cylinder 21 and aligned with receiving port 16 and discharge port 18, and a similar pocket 28 is formed in alignment with ports 17 and 19. Pocket 28 is formed in cylinder 21 on the opposite side of pocket 27 such that when pocket 27 opens to receiving port 16, pocket 28 will open to discharge port 19 and vice versa, and when by rotation of the cylinder 21 pocket 27 opens to discharge port 18, pocket 28 will be opposite receiving port 17. At the bottom of 10 each pocket 27 and 28 is a threaded recess 29 adapted to receive an adjustable headless screw 30, adjustment of which will increase or decrease the size of the pockets 27 and 28 by which the 15 quantity of material to be dispensed can be uniformly determined. A pair of diagonally opposite recesses 31 are provided in cylinder 21, and a threaded bore 32 and a concentric cylindrical bore 33 are provided in the cap 12 in alignment with the center line of recesses 31. A hollow 20 screw 34 is adapted to fit in threaded bore 32 and retains a plunger latch 35 which extends partially into bore 33 and is pressed by spring 36 against the side of cylinder 21 and engages recesses 31 as the cylinder 21 is rotated.

25 In bore 24 between adjusting screws 30 is a compression spring 37, at each end of which is a friction cap pin 38. Pins 38 are maintained by spring 37 against the sides of screws 30, the friction contact of which prevents screws 30 from 30 turning accidentally and changing the desired volume of measuring pockets 27 and 28.

The operation of the device should be obvious. When cylinder 21 is rotated by means of the operating stem 23 the pockets 27 and 28 will alternately be brought into alignment with receiving ports 16 and 17 receiving a definite quantity of the tooth filling material from the container 10 and when the cylinder is rotated 180°, as will be indicated by the plunger latch 35 being 40 snapped into one of the recesses 31, the material will be dispensed through discharge ports 18 and 19. It will be apparent that a quantity of the tooth filling material will at all times be available in one or the other of the pockets 27 and 45 28 in readiness for immediate discharge as needed.

While I have illustrated and described the preferred form of construction for carrying my invention into effect, this is capable of variation and modification without departing from the spirit of 50 the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. A device of the character described comprising a container and a closure therefor, said closure having axially alined filling and discharge ports, a rotatable dispensing cylinder between said ports and having a plurality of measuring recesses alined with said ports, and a resilient 10 friction bearing for said cylinder, there being a slot in said closure adapted to provide said friction bearing.
2. A device of the character described comprising a container and a closure therefor, said closure having a plurality of pairs of axially alined filling and discharge ports, and a dispensing cylinder between said ports, said cylinder having an adjustable measuring recess in alinement with each of said pairs of ports.
3. A device of the character described comprising a container and a closure therefor, said closure having a plurality of pairs of axially alined filling and discharge ports and a cylindrical bore, and a dispensing cylinder between said ports, 25 said cylinder having an adjustable measuring recess for each of said pairs of ports, said recesses each having an adjustable measuring screw therein, one of said recesses adapted to register with its filling port when the other is in register with its discharge port and vice versa.
4. A device of the character described comprising a container and a closure therefor, said closure having axially alined filling and discharge

ports and a cylindrical bore, a dispensing cylinder between said ports, said cylinder having adjustable measuring recesses, said recesses each having an adjustable measuring screw therein, a bore in said cylinder between said measuring recesses, 5 and friction means in said bore, adapted to engage said screws.

5. A device of the character described comprising a container and a closure therefor, said closure having axially alined filling and discharge 10 ports, a dispensing cylinder between said ports, said cylinder having adjustable measuring recesses, each being alined with a pair of said ports, said recesses each having an adjustable measuring screw therein, a bore in said cylinder between 15 said measuring recesses, and friction means in said bore adapted to engage said screws, said means comprising a spring.

6. A device of the character described comprising a container and a closure therefor, said closure having axially alined filling and discharge ports, a dispensing cylinder between said ports, 20 said cylinder having adjustable measuring recesses each being alined with a pair of said ports, said recesses each having an adjustable measuring screw therein, a bore in said cylinder between 25 said measuring recesses, and friction means in said bore to restrict the movement of said screws, said means comprising a spring, said spring having friction cap pins adapted to engage said 30 measuring screws.

EDWARD L. CHOTT.
